UNITED STATES PATENT OFFICE.

WILLIAM BARKER, OF WATERVLIET, NEW YORK.

DESIGN FOR A COLLAR.

SPECIFICATION forming part of Design No. 19,157, dated June 18, 1889.

Application filed March 18, 1889. Serial No. 303,781. Term of patent 7 years.

To all whom it may concern:

Be it known that I, WILLIAM BARKER, residing at the town of Watervliet, county of Albany, and State of New York, have invented and produced a new and original Design for Apparel-Collars, of which the following is a specification, reference being had to the accompanying drawings, forming part thereof.

10 Figure 1 of the drawings represents in perspective my newly-designed collar ready and in form for use. Fig. 2 represents the same collar in plain-laid out flat.

15 The leading feature of my design consists of a collar having a button-holed bottom part or band and a turn-down top part, the turn-down part on the back side of the collar being much narrower than the band and turned down by a sharp abrupt fold, the line of junction between the narrow top and wide band being substantially a straight line, while on the front side or ends of the collar the turn-down portions are much wider than the band, the line of junction between the top and band

20 parts curving abruptly downward and toward the collar ends, as shown in Fig. 2, whereby the top part of the collar, when turned down,

is necessarily given a broad sweeping fold at the ends, as shown in Fig. 1, the lower side of the band part being described by a straight 30 line, as shown in Fig. 2.

A represents the front portions, and A' the back portion, of the collar-band.

B represents the front portions, and B' the back portion, of the turn-down on top part of 35 the collar.

It will readily be observed that the part B' is much narrower than the part A', and that the parts B are much wider than the parts A; also, that the back part B' folds down closely 40 against the band with a sharp abrupt fold C', being folded on the straight junction-line D, while the front parts B fold outwardly as well as downwardly with a broad sweeping curve C, being folded on the abruptly-curved lines D'. 45

What I claim is—

The design for an apparel-collar herein shown and described.

In testimony whereof I have hereunto set my hand this 16th day of March, 1889.

WILLIAM BARKER.

Witnesses:

GEO. A. MOSHER,
FRANK C. CURTIS.
